UNITED STATES PATENT OFFICE.

JOHN SHERMAN McCHESNEY, OF CHICAGO, ILLINOIS, ASSIGNOR, BY MESNE ASSIGNMENTS, TO CARY MANUFACTURING CO., OF BROOKLYN, NEW YORK, A CORPORATION OF NEW YORK.

PACKAGE-BANDING MACHINE.

Application filed March 19, 1919. Serial No. 283,607.

My invention relates to appliances for banding objects or groups of objects with wire, and in its general aspect aims to provide a simple, positive and easily manipulated appliance for successively accomplishing the various steps involved between the feeding of wire from a continuous supply to the releasing of the properly banded object. In one of its more particular aspects, my invention aims to provide simple means for utilizing a single source of power both for forcing the wire into loop formation about a package or other object and for thereafter retracting the supply end of the wire to tension the band about the object. In this aspect, my invention aims to provide simple and positive means for feeding a predetermined length of wire into a suitable raceway, to provide simple and positive means for gripping the free end portion of the wire and preferably for kinking the same to afford a secure hold against the strain involved during the tensioning of the wire around the package; to afford positive means for retracting the supply end of the wire to a predetermined tension regardless of the size of the object which is being banded, to afford simple means for setting the retracting wire-feeding portion of the mechanism in operation, and to afford automatic means for disconnecting this part of the mechanism when the desired amount of wire has been fed; to afford simple means responsive to the tensioning of the wire for limiting the extent of this tensioning, and to afford simple means responsive to this predetermined tensioning for starting the operations subsequently involved in the severing of the supply portion of wire from the loop portion and in the securing of the loop ends to each other. For these subsequent operations, my invention aims to provide simple means for successively severing the loop portion of the wire from its supply, for thereafter forcing portions of the loop into overlapping relations to each other, and for welding such overlapping portions to each other. In this same connection, my invention aims to provide simple means for applying the welding current to the overlapped wire portions through a roller moving across one surface of the overlapped wire ends; to provide simple means for limiting the time during

which current is supplied to the welding terminals and preferably for disconnecting the current during the return movement of the welding roller; and to provide simple means for returning the wire-gripping, wire-cutting and roller welding portions of the appliance to their initial positions. My invention includes, also, a deformed wire, the deformation of which is co-operable with certain elements or parts whereby said deformation resists slippage of the wire during the operation of tensioning said wire. Said deformations perform the further function of resisting slippage while the wire is under tension and during the operation of fastening or joining the end portions of the wire. Still further objects will appear from the following specification and from the accompanying drawings, in which drawings

Fig. 23 is a perspective view of the cam 44 which raises the slide 82.

Fig. 24 is a perspective view of the slide 82 carried by the guide 16.

Briefly summarizing the manner in which I accomplish the purposes of my invention, I provide a raceway 1, having a gap at its bottom and having at one side of the said gap a tubular guide 2 through which a wire 3 may be shoved into the raceway by a pair of feed rolls 4 and 5. This raceway projects above the level of the lower periphery of a series of conveyer rollers 6 as seen in Figure 3 which facilitates the sliding of the package 7 into position for wire-banding the same.

The wire 3 is taken from a supply reel 8 and the feeding rolls 4 and 5 are rotated to such a predetermined extent as to feed the wire entirely around the raceway and to leave the free end of the wire disposed between a thrust plate 38 and a slide 10 carrying a wedge 11, which wedge is adapted to kink a portion of the wire into a corresponding groove in the thrust plate 38 when the slide 10 is moved transversely with respect to the wire and the thrust plate 38. This kinking holds the free end of the wire, so as to per-

mit of a retracting of the supply portion of the wire and of the tensioning of the wire around the package.

To accomplish this tensioning, I release the feed rolls from their grip on the wire, and then retract the supply portion of the wire by a continuous pull afforded by a series of grippers moving longitudinally of the wire and so arranged that each of the movable grippers clutches the wire before the next preceding gripper releases its hold on the same. These grippers are carried by an endless chain passing over sprockets mounted on two axles, one of which axles is journaled on movable slides which are yieldingly held in their normal positions by spring proportioned to the desired tension on the wire, so that when this tension is reached a compressing of the spring will permit the movably journaled axle to approach the other axle, thereby actuating means for rendering the tensioning mechanism inoperative.

Then I provide connections to this movable axle, whereby the movement of the same not only automatically disconnects the wire-tensioning mechanism from the source of power, but also starts the portion of my appliance which holds the wire under tension. severs the wire from the supply, and welds joins the ends of the wire loop while the loop is maintained under tension. For these latter purposes, I provide cam-actuated means for gripping (and desirably kinking) the portion of the wire loop to which the supply of wire is connected, such as a cam 12 raising a plunger 13 having a tip adapted to kink a part of the wire into an adjacent groove in the bottom of a slidably thrust plate 38. It is to be noted by reference to Figure 11 that the thrust plate is provided in its under surface with a recess with which coacts the tip of a plunger 13, whereby a band is adapted to be deformed or "kinked". to the end that the recessed thrust plate and the plunger co-operate to deform said band and to retain said band against movement or displacement. Again, it will be noted by reference to Figures 11 and 10, that wedge 11 of the slide 10 and the recess in the under-surface of the thrust plate 38 constitute, also, means for deforming a band, said deforming means being co-operable in holding the band at or near one end portion thereof when tension is applied thereto. Said wedge formed slide and the recessed thrust plate thus perform the important function of retaining a deformation of a band at or near an end portion thereof so as to preclude slipping of the band under the strain applied to tension the same. I also provide cam means, such as a cam 14 for raising a guide 16, which carries a reciprocable welding electrode, and for also raising a knife 15. The knife 15 is so disposed as to force

the severed end of the wire loop into approximate overlapping relation to the original free end of the wire, and the cam 14 is of such shape that it will hold both the 5 knife 15 and the guide 16 in their raised positions while the movable electrode is reciprocated across overlapped wire portions to weld these to each other along a transverse band; after which the continued movement 10 of the cams 12 and 14 permits gravity to lower the plunger 13, the knife 15 and the guide 16 (together with the welding mechanism carried by this guide), so as to allow the banded package to be removed after a 15 withdrawable of the thrust plate 38 and the slide 10. To avoid a waste of current, I also provide a commutator 89 carried by the same shaft 17 on which the said cams are mounted, so as to limit the duration of the 20 current to the initial movement of the welding electrode 18 in one direction. Then I also provide means for automatically stopping the cam shaft 17 after it has caused the cams to complete their cycle of operations.

25 Referring first to the means for disposing the wire in loop formation and for gripping the free end of the wire, it will be seen from Fig. 11 that a movement of the feed rolls 4 and 5 in the direction of the arrows will 30 propel the wire towards the left of this drawing, this being accomplished while the plunger 13, the welding roller 18 and the knife 15 are lowered, while the thrust plate 38 and the slide 10 are slid back out of vertical alignment with the bore of the raceway. Owing to the stiffness of the commercial wire, this will closely follow the inner wall of the raceway, so that the feeding of a predetermined length of wire will always cause 35 the free end to be disposed at substantially a predetermined point. By suitably proportioning the number of revolutions of the rolls 4 and 5 to the diameter of these rolls and to the size of the raceway, I can therefore readily cause the free tip of the loop to extend partly across the gap in the raceway. To insure an effective gripping of the wire between the feed rolls, I journal the 40 shaft 19 of the lower roller 5 on a slide 20 which may be raised or lowered by means of a cam 21 (see Fig. 11) turned by a handle 22, as shown in Fig. 6. This cam 21 is interposed between the slide 20 and a thrust plate 23, which plate may be adjusted in position by means of screws 24, to vary the distance between the feed rolls according to the thickness of the wire. Upon turning the cam 21 to a position at right angles to that 45 shown in Fig. 11, gravity will lower the slide 20 and consequently the roll 5, thus affording ample clearance for initially introducing the wire from the reel 8, after which the returning of the cam 21 to the position of Fig. 6 brings the feed rolls into 50 gripping relation to the wire.

Power is supplied from a drive pulley 25 (Fig. 9) through bevel gears and a chain 26 to a clutch jaw 27 loosely mounted on the shaft 28 of the upper feed roll and opposed to a clutch jaw 29 splined to the shaft 28. 55 To start the feed rolls in operation, the jaw 29 is moved into clutching engagement with the continuously rotating clutch jaw 27 by a fork 30 on the end of a rod 31. This rod is normally held in the retracted position shown in Fig. 9 by a spring 32, but carries a tapering knob 33 which interlocks with a latch 34 to hold the clutch rod 31 in the position in which it maintains the clutch jaws 27 and 29 engaged with each other. Consequently, the feed roll shafts will be rotated until the latch 34 is disengaged so as to allow the spring 32 to effect a disengagement 60 of the clutch jaws.

To effect this disengagement, I provide a 65 trip 35 carried by a timing chain 36. This timing chain is intermeshed with a sprocket fastened to the shaft 28 of the upper feed roll, and starts moving as soon as the clutch jaws 27 and 29 are engaged with each other, 70 so that the time during which the said clutch keeps the feed rolls in operation depends on the length of the timing chain, which is proportioned to the diameter of the feed rolls and the size of the raceway. To permit the 75 driving feed roll 4 to rotate backward during the tensioning of the wire, I do not fasten the driving sprocket rigidly to the clutch jaw 29, but mount it rotatably to the frame of the machine adjacent to the latter as shown in Fig. 6 and connect the two by a ratchet pawl 99 pivoted on the sprocket and pressed by a suitable spring (not shown in the drawing) against teeth on the clutch 80 jaw 29. This ratchet connection is so directed as to lock the sprocket to the jaw only for joint rotation in the direction in which the roll feeds the wire into the raceway.

When the wire has thus been fed into a 85 loop formation, which may readily be done even after the package 7 is placed in its operative position on the machine, the thrust plate 38 is slid across the gap in the raceway, so as to be disposed between the wire loop and the bottom of the package, and the free 90 end of the wire loop is gripped between this thrust plate and another gripper member. To make this gripping sufficiently effective for preventing a slipping of the wire when the latter is tensioned about the package, I 95 desirably provide a tapering groove in the bottom of the thrust plate 38 (as shown in detail in Fig. 10) and equip the companion gripper element 10 with a wedge 11 adapted to kink the wire into the said groove. To 100 facilitate the sliding of the wire through the relatively narrow space between the thrust plate 38 and the slide 10, I desirably round the edge of the former as shown in Fig. 10. The thrust plate 38 is slidably in- 105

4

terlocked with stationary plates 37 and has a tongue adapted to engage under another stationary plate 9, thereby holding this thrust plate firmly against the strain involved during the kinking and gripping of the wire. When slid into the operative position of Fig. 9, this thrust plate is interposed between the package and the wire loop (as shown in Fig. 11), but is later withdrawn to permit the removal of the banded package. The thrust plate 38 carries pins 39 (as shown in Figs. 7, 9 and 21), which pins project downwardly into cam grooves 40 in a slide 41. The gripper slide 10 carries a pin 42 which projects upwardly into a cam groove 43 in the same slide 41. Consequently, a movement of this slide 41 will move both the slides 38 and 10 transversely across the gap in the raceway, but the cam grooves 40 and 43 are formed in relatively reverse directions (as shown in Figs. 9 and 10) so that the movement of the slide 41 towards the left in Fig. 9 will first move the slide 38 across the gap or into a position between the wire and the package, and will thereafter move the slide 10 across the gap under the wire, so as to cause the wedge 11 to kink and grip the wire between itself and the adjacent part of the thrust plate 38.

30 This movement of the slide 41 is effected by the lever 44 arranged as in Fig. 4, this lever being mounted on a pivot 45 and locked in either one of two positions by a spring-pressed-latch 46 which may be released by a handle 47. Fig. 4 shows this lever in a position corresponding to Figs. 1 and 9, or in one in which it has already moved the slide 41 and has also moved a bar 48 which controls the means for causing the movable wire grippers to engage the wire.

45 In the embodiment illustrated, each of these wire grippers consists of a jaw 49 rigidly secured to a carrier plate 50, and a companion jaw 51 also carried by the same plate but so mounted that it can be moved towards the stationary jaw or away from the latter. For this purpose, I desirably pivot a bell-crank 52 upon the plate 50 and connect this with the movable jaw 51 by a pin 53. Then I also provide a link 54 pivotally connected to both the bell crank 52 and the movable jaw 51, so as to maintain the jaws parallel to each other while they are being moved by a swinging of the bell-crank 52.

55 To effect this swinging, I interpose a spring 54 between one end of the bell-crank and a lug 55 on the plate 50, and equip the other end of the bell crank with a roller 56 adapted to engage a cam plate 57. The cam plate 57 is slidably mounted on bolts 58 extending through slots 60 oblique to the face of the jaws 49 and 51 and is continuously urged by a spring 59, which cooperates with the said oblique slots 60 in tending to force the cam plate 57 to a position in which the roll-

er 56 would clear the edge of this plate. However, the cam plate 57 may be moved by the bar 48 against the pressure of the spring 59 and into the position of Fig. 13, thus causing the roller 56 to engage the beveled end of the cam plate and to move the bell-crank into the position in which it forces the jaws into gripping relation with the wire.

To secure a rapid and continuous tensioning of the wire, the tensioning chain 60⁷⁵ carries a series of the carrier plates 50, each equipped with the gripper jaws and jaw-moving means as above described, the spacing between them being so proportioned to the length of the cam plate 57 that each of the bell-crank levers will be effectively moved by the cam plate before the next preceding lever is disengaged from the latter. Thus, the drawings show the chains 60⁸⁰ as carrying three sets of these gripping means, each having jaws of such length that they can firmly grip even thin and flat wire without damaging the latter.

To insure an effective banding, it is also desirable to distribute the tensioning of the loop symmetrically with respect to the package, for which purpose I provide a stop 61 against which the tensioning of the loop draws the package, this stop being movably mounted and resisted in movement by a spring 62 interposed between it and a rigid bracket 63. To limit the tensioning of the wire, I provide fixed bearings for the shaft 64 carrying the upper of the two sprockets engaged by the chain 60⁹⁰, this shaft being driven through a worm 65 on the power shaft 66 and a worm wheel 67 fastened to the shaft 64. The companion sprocket carrying the tensioning chain is mounted on a shaft 68 journaled in slides 69 on the frame of the machine, as shown in Fig. 12, these slides being continuously pressed by springs 70 which tend to keep the chain taut. These springs are of such strength that they will yield when the tensioning of the wire reaches a predetermined degree, thus permitting the shaft 68 to move bodily towards the drive shaft 64.

This movement of the shaft 68 swings a lever 71 which has a forked end spanning this shaft as shown in Fig. 12, thereby imparting a longitudinal movement towards the left of the drawings to the thrust rod 72 of Figs. 4, 11 and 13 for the purpose of actuating the wire-cutting and welding mechanism as hereafter described. This latter mechanism is operated through a cam shaft 17 which extends loosely through a worm wheel 73 intermeshing with a worm mounted on the same shaft 74 with the sprocket 120 which drives the timing chain 36. The hub of the worm wheel 73 is notched at one end to match notches in a clutch sleeve 75 which is splined to the shaft 17 and which is normally slid out of engaging relation with the 130

notched hub of the worm 73 by a spring 76, as shown in Fig. 11. Upon moving the rod 72 against the resistance of the last named spring, the clutch sleeve 75 is interlocked 5 with the hub of the worm wheel 73, as shown in Fig. 4, thereby operatively connecting the shaft 17 with the continuously rotating shaft 74, while the rod 72 is temporarily latched in its said clutch-operating 10 position by a pivoted latch 77. This pivoted latch is held in its said position by a spring 78 until the shaft 17 has made a complete revolution, when this latch is tripped by a lug 79 on the barrel of the 15 clutch, thereby releasing the enlargement 72 (see Figs. 4 and 11) on the rod 72 which was in engagement with the latch 77. This enlargement is desirably threaded on the rod 72 as shown in Fig. 11 so as to permit an 20 accurate adjustment of its position, while the threaded engagement of the rod 72 with the strap 95 connecting this rod to the lever 71 permits an adjustment for varying the degree of compression of the springs 70 to 25 which these will be responsive.

While the clutch barrel 75 is thus rotating, the lug 79 raises the bar 48 which controls the position of the cam plate 57, thereby unlatching this bar from its sprung 30 pressed connection with the lever 44 (as shown in Figs. 19 and 20) and permitting the spring 59 to slide the cam plate 57 out of its operative position. Consequently, although the chain 60 will continue to carry 35 the gripper jaws successively along opposite sides of the wire, these jaws can no longer be forced into gripping relation to the wire, so that the further tensioning of the wire is discontinued after the cam shaft 17 has 40 made a part of its rotation. During the interval, the cam 12 forces the plunger 13 upwardly, thus pressing the supply portion of 45 the wire loop against the thrust plate 38 as shown in Fig. 11 and holding it so pressed during the operation of the welding mechanism. To prevent a slackening of the tension on the wire when the tensioning mechanism is operatively disconnected after tightening the loop, I provide the driving 50 sprocket with a hub 100 having ratchet teeth engaging a pawl 101, as shown in detail in Fig. 8.

For the welding mechanism, I provide a transformer having one end of its secondary winding 80 connected to the frame of the machine, while the other end is connected to a relatively insulated lever 81 carrying a roller 18 which serves as the movable electrode. The lever 81 is mounted upon a slide 55 82 and is normally pressed upward by a spring 83 as shown in Fig. 5. This slide 82 is movable transversely of the raceway in a guide 16, but is normally pressed forwardly of the machine by a spring 84 engaging 60 a lug 85 on the guide 16. The guide 16 is

slidable vertically of the machine, for which purpose I desirably provide this guide at opposite sides with grooves respectively engaging the plunger 13 and a companion plunger 86, which latter plunger carries the 70 knife or cutter 15 and is prevented from rotation by the engagement of the forked tips of the knife with the slide 10. The knife or cutter desirably has a beveled cutting edge of a width somewhat greater than that 75 of the wire, flanked by a pair of projections (as shown in Figs. 16 and 17), which projections will prevent the cutter from being spoilt by grinding the same on a wheel. The plunger 86 is desirably so long that its 80 lower end strikes the shaft 17 while the fork tips flanking the knife are still in engagement with the slide 10, or long before the guide 16 reaches the lower limit of its travel. Thus arranged, these fork tips help to guide 85 the wire laterally and prevent the slope of the knife from moving the wire sideways during the shearing.

With the parts thus arranged, it will be evident from Fig. 11 that the rotation of the cam 14 will raise the guide 16, thereby also raising the slide 82 which carries the movable electrode, and that it will raise the knife 15. In doing the latter, the cutting edge of 90 the knife presses the supply portion of the wire against the slide 10 and shears the wire between the two, after which a continued movement of the knife (as shown in Fig. 17) presses the freshly severed portion of the 95 loop towards the initial free end portion of the wire. While the cam 14 is holding the parts in this raised position, a trip 87 fastened to the cam 14 engages a downwardly directed lug on the slide 82 (as shown in 100 Fig. 5), thereby moving the slide 82 transversely of the wire and causing the welding roller 18 to engage the under surface of the 105 freshly severed wire portion under a pressure exerted by the spring 83. This movement continues until the roller has passed entirely across the wire, by which time the tip of the trip 87 passes the bottom of the 110 said lug, thus permitting the spring 84 to return the slide 82 to its initial position.

It is to be noted that in my mechanism an end portion of the band (preferably a deformed portion) is held by band-retaining means comprising a recessed thrust plate 38 and a wedge formed slide 10, that the band in looped formation passes around the package and over the plunger 13 and knife 15, and below a part of the band retained by slide 10, and that the two terminal portions of the loop are in side by side relation, whereby said terminal portions are positioned to 115 effect the union thereof by the operation of appropriate band-secur ing means. In the example shown, this band-secur ing means is embodied in the form of a welding electrode roll 18 to which electrical current is 120 125 130

supplied and which is under pressure of spring mechanism (lever 81 and springs 83) and to which roller 18 a traversing motion is given subsequently to the assemblage of the 5 band for its terminal portions to lap one another, said springs 83 tending to press the terminal portions of the band into physical contact and under yielding pressure. The welding electrode is thus actuated to press 10 the band terminals into physical contact and to traverse the lapping portions so as to heat said lapping portions and press them together for producing a joint or union by welding operation.

15 The band is cut by a shearing action of the knife 15, which co-operates with the element 10 of the band gripping device comprising the recessed thrust plate 38 and the slideable element 10 with the wedge 11, said cutting edge of the knife 15 shearing past an edge 20 of slide 10 as shown in Figure 4. The knife is actuated automatically by cam 14 which is timed to impart an upward movement to the knife at a period subsequently to the 25 operation of the tensioning means and to the gripping action of plunger 13 on the band, said knife acting to sever the band prior to the operation of the band-securing 30 means afforded by the welding roll 18 and mechanism associated therewith.

To avoid a waste of electrical energy, I desirably mount on the free end of the shaft 17 a head carrying a commutator 89 having imbedded in it a metal plate 90 which has 35 its central portion continuously engaged by a brush 91 connected to one terminal of the low voltage generator 92, which supplies the primary current for the said transformer. The other terminal of the circuit 40 comprising the generator 92 and the primary of the transformer is connected to a brush 93 which is slidably mounted in a forked bracket 94, so that this brush may be adjusted to vary the length of time during 45 which the circuit is completed in the course of a single rotation of the commutator, thereby permitting the time to be adjusted according to the width of the wire. The plate 90 is desirably so shaped as to afford the electrical connection only while the welding roller 18 is traversing the wire during its 50 initial movement, leaving the current cut off during the return stroke, so that the pressure of the roller during the return movement merely helps to press the weld-joined wire loop portions tightly together during the initial period of their cooling. As soon as the shaft 17 has completed this rotation, the lug 79 trips the latch 77, thus releasing 55 the clutch sleeve 75 and operatively disconnecting the cam shaft 17 from the source of power.

In operating the machine, this starts with the tip of the supply wire vertically in alignment with the top of the knife, with the

thrust plate 38 drawn back so as to expose the gap in the top of the table, and with the lever 44 swung over to the right. After placing the box or other package in the desired position for banding, the operator first moves the lever 44 half-way towards the left in Fig. 4, or to a position in which the latch 46 is intermediate of the notches adapted to engage the same. This moves the slide 41 to the position of Fig. 10, or one in which it has slid the thrust plate 38 across the gap in the raceway under the package, but has not yet moved the slide 10. He then moves the rod 31 into its clutch-engaging position, thus starting the rotation of the feed rolls 50 and also the movement of the timing chain. (Owing to the slow movement of the timing chain, the momentum does not appreciably affect the latter, so that the lug 35 always stops in the position of Fig. 11.) As soon as the lug on the timing chain has completed its circuit and released the latch 34, the handle 31 snaps back into its position of Fig. 9. This snapping tells the operator that the required amount of wire has been fed into 55 the raceway. He then moves the lever 44 clear over into its operative position of Figs. 1 and 4, thus starting the tensioning mechanism, which effects the desired tensioning, then automatically actuates the clutch 75 on 60 the wire-cutting and welding mechanism and likewise automatically shuts off the tensioning mechanism. As soon as this clutch 75 has caused the shaft 17 to complete a single revolution, the thrust rod 72 is released and 65 snaps back into its normal position, thus advising the operator that the entire banding operation has been completed. He then throws the lever 44 back to its original position, thus retracting the thrust plate 38 and the slide 10, thereby opening the gap in the 70 table so that the banded package can either be lifted off the table or slid into position for affixing another band, leaving the machine in immediate position for renewing this 75 cycle of operations.

In practice, this entire cycle of operations requires but a fraction of a minute, and as the operator only needs to manipulate two handles, my appliance readily lends itself 80 to the employment of unskilled help. However, while I have illustrated and described my machine in a desirable embodiment, I do not wish to be limited to the details of the construction and arrangement here described, it being obvious that the same might be varied in many ways without departing 85 from the spirit of my invention within the scope of the appended claims.

The deformed wire of my invention for 90 banding packages is illustrated more particularly in Figure 11 of the drawings, wherein the wire 3 is shown as having been looped or passed around the package, into contact therewith and with the end portions 95

of said wire in position to be lapped prior to the operation of fastening said wire ends as by the welding operation. As shown, the wire is deformed at two places, one of which 5 is at the recessed thrust plate 38 and the plunger 10, and the other deformation is at the thrust plate 38 and the plunger 13. As shown, the deformations at two places are produced in the wire by the movement 10 of plungers 10, 13, relatively to the thrust plate, and said deformations are characterized by recesses and shoulders in the wire which co-operate with the thrust plate and said plungers in a way to hold said wire 15 from slipping during the tension operation and also during the operation of fastening the wire ends.

I claim as my invention:—

1. In a wire-tensioning appliance, plural 20 means for gripping a wire and moving the same in a given direction, means for successively bringing the said gripping means into action while passing a given point, and means responsive to a predetermined tensioning of the wire for rendering the last 25 named means inoperative.

2. In a wire tensioning appliance, wire gripping means arranged in opposed pairs, means for successively bringing each of the 30 said pairs to positions at opposite sides of the wire, and cam means for forcing each of the said pairs to grip the wire when so positioned.

3. In a package banding machine, wire 35 tensioning means including an endless member movable in the direction of feeding a wire to an object to be banded, a plurality of wire grippers carried by and movable with said endless member, means for actuating said grippers for gripping engagement with the wire while said grippers are moving past a given point, and means for releasing said grippers from the wire.

4. In a package banding machine, wire 45 tensioning means including an endless member movable in a direction for feeding wire to an object to be banded, a plurality of grippers each carried by said endless member, means whereby each gripper is actuated 50 for gripping engagement with the wire, and means responsive to tension on the wire for actuating said gripper for releasing the wire.

5. In an appliance for banding an object 55 with a wire loop, means for gripping the free end portion of the wire formed into a loop, continuously moving plural means operable for successively gripping the wire and moving the same in one direction to 60 tension the loop about the object, actuating means for successively bringing the said gripping means into action, and single manually operable means for actuating the said gripping means and the said actuating means.

6. In an appliance for wire banding, means for holding the free end of a wire to be formed into a loop, continuously movable plural means operable for gripping the wire and for tensioning the same about an 70 object, actuating means for successively moving the gripping means into engagement with the wire, manually-operated means whereby the actuating means is started and stopped, and means responsive to a desired 75 tension on the wire for automatically arresting the actuating means.

7. In an appliance for wire banding, means for holding one end of a looped wire, 80 a plurality of continuously moving grippers each adapted for engagement with the wire for tensioning the same, actuating means cooperable with said grippers successively whereby the grippers are engaged periodically with the wire and are effective in pulling said wire for a determined period, means operable at will for starting and stopping the movement of said grippers, and means responsive to a desired tension on the wire 85 for arresting automatically the movement of 90 said grippers.

8. In a wire tensioning appliance, continuously moving plural means adapted to grip the wire and to move the same in a given direction, actuating means for successively bringing the gripping means into action, cam means for moving the actuating means into operative position, and spring means for returning the actuating means to 100 an inoperative position.

9. In an appliance for tensioning a wire, an endless member having a straight stretch parallel to a straight portion of the wire which is to be tensioned, plural wire gripping means carried by the endless member and arranged for gripping the wire while traversing the said straight stretch, a pair of sprockets over which the endless member is trained, a pair of shafts respectively carrying the sprockets, and supporting means 105 for the shafts arranged for permitting a relative approaching thereof upon a predetermined tensioning of the wire.

10. In a wire tensioning appliance, wire gripping means, an endless member carrying the same, a pair of sprockets over which the endless member passes, a pair of shafts respectively carrying the said sprockets, shaft-supporting means arranged for permitting a relative approaching of the shafts in 110 response to a predetermined torque on the endless member, and means actuated by the approaching of the shafts for operatively disconnecting the action of the wire gripping means.

11. In a wire tensioning appliance, a support, a drive shaft journaled thereon, a bearing mounted on the support for slideable movement towards the drive shaft, a second shaft journaled in the bearing, a pair of 115 120 125 130

- sprockets respectively carried by the two shafts and having one thereof fast upon the drive shaft, an endless chain passing over the sprockets, wire gripping means carried by the endless chain, and spring means associated with the said bearing to resist a sliding thereof by the resistance of the wire to the tension imparted thereto through the gripping means.
12. In an appliance for wire-banding an object, wire tensioning means, wire-loop closing means, a clutch controlling the operation of the loop closing means, a starting lever, a releasable connection between the starting lever and the wire tensioning means, means responsive to a predetermined tensioning of the wire for latching the clutch in operative position, and common means carried by the clutch for releasing the said connection and for thereafter unlatching the clutch.
13. In an appliance for banding an object with a wire loop, a thrust member, a gripping member; and single means for disposing the thrust member between the object and a part of the wire loop and for thereafter gripping the wire between the said members.
14. In an appliance for banding an object with a wire loop, a support for the wire loop, a thrust member and a gripping member both slidable upon a suitable support transversely of the wire loop; and means for successively interposing the thrust member between the object and a portion of the wire loop, and for thereafter sliding the gripping member into gripping relation to the thrust member to grip the said portion of the wire loop between them.
15. In an appliance for banding an object with a wire loop, means for supporting the wire loop, a slide mounted on suitable supporting means and movable parallel to the plane of the wire loop; and a pair of wire-gripping members movably mounted on the supporting means and adapted to be moved into gripping relation with a portion of the wire loop, and cam means connecting the slide with the gripping members for causing a movement of the slide to move the gripping members to their said wire-gripping relation.
16. Mechanism as per claim 15, with one of the gripping members adapted to be disposed between the object and the wire loop when in gripping position, and with the cam means arranged for first moving the said gripping member into its said position and thereafter effecting a gripping of the wire between the gripping members.
17. In an appliance for banding an object with a wire loop, a thrust plate adapted to be disposed between the object and a portion of the wire loop and presenting recesses directed towards the wire, and separate means for kinking separated portions of the wire respectively into the recesses in the thrust plate.
18. In an appliance for banding an object with a loop of wire, a pair of wire-gripping members disposed for gripping the terminal loop portion of the wire, and a reciprocatory knife cooperating with one of the said members for severing the other loop terminal from the supply of wire.
19. In an appliance for banding an object with a loop of wire, a pair of wire-gripping members disposed for gripping the terminal loop portion of the wire, and a reciprocatory knife cooperating with one of the said members and guided by the latter for severing the other loop terminal from the supply of wire.
20. In an appliance for banding an object with a wire loop, means for feeding wire into a loop about the object, a spacer member adapted to be inserted between the loop and the object, wire tensioning means, and single manually operable means for inserting the spacer member and automatically operating for starting the tensioning means.
21. In an appliance for banding an object, means for feeding wire into loop formation about the object, means for gripping the free end portion of the wire, means for tensioning the wire about the object, means for gripping another portion of the wire loop, and means for halting the tensioning after the actuating of the last named gripping means.
22. In an appliance for making a wire band, means for disposing the free end of a supply of wire in loop formation with the tip thereof overlapping and relatively inclined to the supply portion of the wire, means for gripping the tip portion at a distance from the said tip and for gripping the supply portion at a point beyond the said tip, means for severing the supply portion of the wire and for pressing the severed loop portion towards the said tip portion, and yielding means for completing the said movement of the overlapping wire portions towards each other.
23. In an appliance for making a wire band, means for disposing the free end of a supply of wire in loop formation with the tip thereof overlapping and relatively inclined to the supply portion of the wire, means for gripping the tip portion at a point beyond the said tip, means for severing the supply portion of the wire and for pressing the severed loop portion towards the said tip portion, yielding means for completing the said movement of the overlapping wire portions towards each other, and means for thereafter securing the overlapped portions to each other.
24. In an appliance for making a wire band, means for disposing the free end of a

- supply of wire in loop formation with the tip thereof overlapping and relatively inclined to the supply portion of the wire, means for gripping the tip portion at a distance from the said tip and for gripping the supply portion at a point beyond the said tip, means for severing the supply portion of the wire and for pressing the severed loop portion towards the said tip portion, yielding means for completing the said movement of the overlapping wire portions towards each other, and means for electrically welding the overlapped wire portions to each other.
25. In a package banding mechanism, band-feeding means operable to position a band in loop formation with the terminal portions of said loop in side by side relation, band-retaining means engageable with a deformation of said band for holding said band against slipping when tension is applied thereto, band tensioning means, and band securing means for joining said side by side positioned portions of said band.
26. In a package banding mechanism, band-retaining means including a recessed member engageable with a deformation of a band for holding said band against displacement when tension is applied thereto, band-tensioning means, and band-securing means for uniting side by side portions of the band when looped with respect to a package.
27. In a package banding mechanism, band-retaining means including a recessed member engageable with a deformation of said band for holding the same against slipping when tension is applied thereto, band-tensioning means, band-uniting means positioned for joining the terminal portions of a loop formed by said band, and reciprocating band-cutting means positioned for severing the band subsequently to the operation of the band-tensioning means.
28. In a package banding mechanism, band-retaining means engageable with a deformation of a band for holding the same against displacement when tension is applied thereto, band-tensioning means, band-securing means for joining the terminal portions of a loop into which the band is formed around a package, and band-cutting means operable for severing the band subsequently to the action of the tension means.
29. In a package banding mechanism, band deforming and retaining means for holding an end portion of a looped band to prevent slipping under tension, band-tensioning means and band-securing means for joining end portions of a loop into which said band is adapted to be formed.
30. In a package banding mechanism, band deforming and retaining means for holding an end portion of a looped band to prevent slipping under tension, band-ten-
- sioning means, band-securing means for joining end portions of a loop into which said band is adapted to be formed, and reciprocating band-cutting means operable for severing the band adjacent the union ultimately produced for securing the end portions of said loop.
31. In a package banding mechanism, a plurality of band-deforming and retaining devices each operable for deforming a band and engageable with said deformation to hold the band against displacement under tension, band-tensioning means, and band-securing means for uniting the end portions of a loop into which said band is adapted to be formed.
32. In a package banding mechanism, a plurality of band-gripping devices engageable with deformations of a band at points adjacent a union ultimately produced by and between terminal portions of a looped band, in combination with band-tensioning means and band-securing means operable for joining the terminal portions of a looped band intermediate said deformations of the band.
33. In a package banding mechanism, the combination of band-securing means, and band-retaining means engageable with a deformation of said band during the operation of said band-securing means.
34. In a package banding mechanism, the combination with band-securing means, of band-retaining means provided with a recess engageable with a deformed portion of said band for holding the latter during the operation of said band-securing means.
35. In a package banding mechanism, the combination with band-securing means, of band-retaining means provided with a recess engageable with a deformation of said band adjacent an end portion thereof, and band-cutting means operable to sever the band adjacent the union effected by the band-securing means between terminal portions of said band.
36. In a package banding mechanism, the combination with band-securing means, of band-retaining means engageable with a deformation of a band, and means for holding and tensioning another portion of said band prior to the union of the band terminals by said band-securing means.
37. In a package banding mechanism, band-retaining means engageable with a deformation of a band to hold an end portion of said band, other means engageable with another portion of the band and operable for placing tension on said band, band-securing means operable for joining two portions of the band intermediate the band-retaining means and said other tensioning means, and band-cutting means for severing the band subsequently to tensioning the same.

38. In a package banding mechanism, band-retaining means engageable with a deformation of a band for holding an end portion of said band when tension is applied thereto, band-tensioning means engageable with another portion of said band for placing tension on said band, and band-securing means for joining adjacent portions of said band intermediate the band-retaining means and the band-tensioning means.

39. In a package banding mechanism, band-retaining means engageable with a deformation of a band for holding an end portion of said band when tension is applied thereto, band-tensioning means engageable with another portion of said band for placing tension on said band, band-securing means for joining adjacent portions of said band intermediate the band-retaining means and the band-tensioning means, and band-cutting means for severing the band at a point close to the joining of the band and operable to sever said band at said point subsequently to the operation of the band-tensioning means.

40. In a package banding mechanism, the combination of band-retaining means engageable with a deformation of a band for holding an end portion of said band when tension is applied thereto, band-tensioning means, band-securing means for joining adjacent portions of a band intermediate the band-retaining means and the band-tensioning means, and an automatic band-cutter for severing the band subsequently to the action thereon of said band-tensioning means.

41. In a package banding mechanism, band-retaining means engageable with a deformation of a band for holding an end portion thereof when tension is applied to

said band, band-tensioning means engageable with another portion of said band for tensioning the band, a gripper engageable with said band and in spaced relation to the band-retaining means, and band-securing means for joining adjacent portions of a band and at a point intermediate the band-retaining means and the gripper.

42. In a package banding mechanism, band-retaining means engageable with a deformation of a band for holding an end portion thereof when tension is applied to said band, band-tensioning means engageable with another portion of said band for tensioning the band, a gripper engageable with said band and in spaced relation to the band-retaining means, band-securing means for joining adjacent portions of a band and at a point intermediate the band-retaining means and the gripper, and band-cutting means for severing said band at a point adjacent the union effected by said band securing means.

43. In a package banding mechanism, a thrust plate, a band-gripper co-operable with said thrust plate for deforming a band and for retaining said band when tension is applied thereto, and band-tensioning means engageable with another portion of said band.

44. In a package banding mechanism, a thrust plate provided with a recess, a band-gripper provided with a wedge, means for effecting a relative movement between the thrust plate and the band gripper whereby to deform a band and to retain said deformed band when tension is applied thereto, and band-tensioning means engageable with another portion of the band for tensioning the same.

Signed at Chicago, March 14th, 1919.
